METALLIC GRATING FOR BOTTLE CRATES

Filed Jan. 2, 1925

2 Sheets-Sheet 2

UNITED STATES PATENT OFFICE.

WILLIAM C. KRAUSE, OF MILWAUKEE, WISCONSIN.

METALLIC GRATING FOR BOTTLE CRATES.

Application filed January 2, 1925. Serial No. 158.

To all whom it may concern:

Be it known that I, WILLIAM C. KRAUSE, a citizen of the United States, and resident of Milwaukee, in the county of Milwaukee, and State of Wisconsin, have invented certain new and useful Improvements in Metallic Gratings for Bottle Crates; and I do hereby declare that the following is a full, clear, and exact description thereof.

10 My invention refers to metallic gratings, which are particularly adapted for use in connection with bottle crates.

Primarily, the object of the invention is to provide a metallic grating which is 15 formed from parallel male and female intermeshed flat bars forming squares or skeleton pockets for bottles, or like containers.

The specific object of my invention is to provide a crate having side and end walls 20 with sets of thin metallic strips intermeshed and locked at the corners of each compartment by the intermeshed engagement, in such manner as to firmly hold the intermeshed strips against movement in all directions to maintain uniformly spaced cavities 25 whereby bottles can easily be inserted. By this arrangement, thin strips can be used for forming the pockets, whereby a great saving in crating space is obtained, while at 30 the same time rigidity of the box is insured, due to the rigid, interlocked connection at the corners of the intersecting or intermeshed bars.

It is common practice in constructing bottle crates to utilize wires of one form or another for developing the skeleton pockets, and in such instances it is necessary to utilize wires of sufficient cross section diameter to insure the proper amount of rigidity. 35 In doing so the wires are of such thickness as to materially reduce the capacity of the crate. With my present invention the gauge of the thin metallic strips is reduced to a minimum, whereby in actual practice an extra row of containers can be added to a 40 crate of the standard pint size, due to the economy in space, it being borne in mind that the thin metal strips, preferably positioned edgewise of the crate, will accomplish the desired saving.

It is understood, however, that in certain instances, my improved grating can be built up with the male strips positioned flatwise

in place of edgewise, as previously stated, the edgewise positioning of the male members being for the purpose of economizing 55 crating space.

With the above objects in view, the invention consists in certain peculiarities of construction and combination of parts, as 60 will be fully set forth with reference to the accompanying drawings and subsequently claimed.

In the drawings:—

Figure 1 is a fragmentary plan view, 65 partly in section, of a crate equipped with a grating embodying the preferred form of my invention, the male and female members in this exemplification of the invention being positioned edgewise to economize space 70 within the crate, whereby a greater number of cells is obtained in a given area.

Figure 2 is a cross section of the same, the section being indicated by line 2—2 of Figure 1.

Figure 3 is a detail longitudinal section, 75 the same being indicated by line 3—3 of Figure 1.

Figure 4 is a detail cross section of the grating, as indicated on line 4—4 of Figure 80 3, the male bar being shown in its initial flat position prior to its rotation to the vertical or edgewise position.

Figure 5 is a fragmentary plan view, 85 partly in section, of another form of my invention, wherein the male members are normally positioned flatwise with relation to the female members.

Figure 6 is a section of the same, the section being indicated by line 6—6 of Figure 5.

Figure 7 is another detailed sectional view, the section being indicated by the line 7—7 of Figure 5, and

Figure 8 is a fragmentary cross sectional view of one of the interlocked bar joints, 95 the male bar being shown in its initial position prior to being twisted or turned downwardly to its flat normal position.

Referring by characters to the drawings, A represents one of the side walls of a crate, 100 and B the end wall thereof, it being understood that in referring to the side and end walls in the claims, this identification may be construed to mean either wall. The body of the crate forms no part of my invention and is built up in the usual manner.

The side walls A have permanently secured thereto a series of thin flat female bars 1 in parallel arrangement and equally spaced from each other and from the end walls. 15 This series of bars are formed with a series of alined T-shaped slots 2, the stem slot 2' being positioned vertically and midway between the cross-slot portion of the teeth. The stem slot is approximately the same 20 depth as the cross slot branches, as shown. In each crate there are two or more series of the female bars arranged in tiers, as best shown in Figure 2 of the drawings.

The grating is completed by a parallel 15 series of thin flat male bars 3, which male bars, in this exemplification of my invention, have their ends slightly tapered, as shown in Figure 3 of the drawings, and said bars are also formed with a series of notches 20 4 equally spaced apart for interlocking engagement with the T-shaped slots of the female bars.

In assembling the male bars, each one of 25 the series is initially positioned flatwise, as shown in Figure 4 of the drawings, and the bar is then threaded through the entire series of slots in the female bars, the notches being positioned in alinement with the T-shaped slots. The male bars are then 30 twisted or rotated downwardly, as indicated by the arrow in Figure 4 of the drawings, and their notches 4 will thus permit the bar to rotate past the metal angle of the T-shaped slot, whereby said bar will assume a vertical or edgewise position, and in assuming 35 such position, it will be locked with relation to the T-shaped slot of each of the female bars.

The end wall sections of the crate are provided with sockets b, as shown in Figures 1 40 and 3 of the drawings, and said end walls are also provided with rails c extending across the inner surface of the walls just below the sockets. The end walls are now 45 slipped in position between the side walls A and in this operation the ends of the male bar members are caused to enter the slots b.

As shown in Figure 3 of the drawings, 50 the lower edges of the male bars 3, when forced in position, are engaged by the rails c and said bars are thus slightly lifted, whereby their upper edges will engage the top wall of the T-shaped slot. The end 55 walls B of the crate are then suitably secured by corner irons to the side walls A, whereby the two series of thin metallic bars form a plurality of rectangular cells or pockets for bottles, or other articles for 60 which the crate is intended. The bottles, or other articles, carried in the skeleton pockets, rest and are supported by a series of bars in the form of heavy wires C, one of 65 which extends centrally with relation to each row of pockets, and the ends of these

bars C are secured in the ordinary manner to the end panels of the crate.

From the foregoing description, it will be seen that after the crate has been completed, the two series of bars will be firmly held in a vertical or edgewise position and that the interlocking notches and slots will thereby rigidly secure the male and female bars at their intersecting points, which form the corners of each cell, and it is manifest that owing to the fact that these bars are held against movement in all directions at short intervals, the bars used can be of minimum strength, which will at the same time be sufficient to resist strains, due 80 to the reinforcement at frequent intervals, which reinforcements are of rigid construction at the corner of each cell. Hence, flexure of the bars, when subjected to the strain, is resisted.

Referring now to Figures 5 to 8 of the drawings, I have illustrated a crate similar in all respects to the crate previously described, with the exception that in this exemplification of my invention the T-shaped slots 5 formed in the female members are positioned with the stems 5' of the slots extending horizontally. The male series of bars 3 are in this instance formed with companion pairs of notches 6-6', whereby a center stem or core is developed in the male bars. In this modification of my invention, the male bars are designed to be normally held flatwise or in horizontal position, while the female bars are 100 vertically or edgewise positioned. Hence, in assembling a structure of this character the male bars are inwardly threaded through the slots of the female bars in an edgewise position, as shown in Figure 8 of 105 the drawings, and thereafter the bars are twisted or turned downwardly, as indicated by the arrow in Figure 8, to assume a flat position, as shown in Figures 5 to 7, inclusive, of the illustration, in which flat position the male bars are held by their correspondingly positioned sockets. However, after the two series of bars are secured, they are rigidly locked against movement 110 in all directions, due to the interlocking 115 engagement between the notches and T-shaped slots at the corners of each pocket. The bottle, or other articles, rest upon and are supported by a series of heavy wire rods c' which are usual in the construction 120 of crates of this general type, it being understood that these supporting rods c and c', referred to in describing the above forms of my invention, extend through 125 apertures in the lower tier of the female bar, as best shown in Figures 2 and 6 of the drawings.

While I have shown and described my invention specifically as to details, it is understood that I may vary the structural 130

features without departing from the spirit of the invention, and as defined in the appended claim.

I claim:—

- 5 A crate having side walls, a series of female bars positioned edgewise with relation to the side walls and provided with T-shaped slots with the crossed portion of the slot relatively long and the laterally extending portion relatively short and of rectangular contour, means for securing the female bars to the side walls, a series of thin flat male bars having notched portions therein leaving a connecting web at the notched portion of rectangular contour adapted to fit the laterally extending rectangular portions of the slots in the female bars, the said male bars being adapted to

be threaded through the slots of the female bars in a flatwise position and turned about 20 their longitudinal axis to position the connecting web at their notches within the rectangular transverse portions of the slots in the female member, the width of the web at each notch holding the web portions in intimate engagement with the transverse portion of the slot to provide a bearing on opposite sides of the web portion throughout a material distance, and means for securing the end walls to the side walls and 30 to the male members.

In testimony that I claim the foregoing I have hereunto set my hand at Milwaukee, in the county of Milwaukee and State of Wisconsin.

WILLIAM C. KRAUSE.
